UNITED STATES PATENT OFFICE

121,942

DESIGN FOR A RADIATOR GRILLE FOR A TRUCK

William O. Block, Detroit, Mich.

Application May 27, 1940, Serial No. 92,644

Term of patent 7 years

To all whom it may concern:

Be it known that I, William O. Block, a citizen of the United States and a resident of Detroit, county of Wayne, and State of Michigan, have invented a new, original, and ornamental Design for a Radiator Grille for a Truck, of which the following is a specification, reference being made to the accompanying drawings, forming a part thereof, in which—

I claim:

The ornamental design for a radiator grille for a truck, as shown.

WILLIAM O. BLOCK.
